UNITED STATES PATENT OFFICE.

GEORGE HERBERT BENTLEY AND EDMUND GARDNER APPLEBY, OF WESTMINSTER,
LONDON, ENGLAND.

APPARATUS FOR AGITATING THE FUEL IN GAS-GENERATORS.

1,391,236.

Specification of Letters Patent. Patented Sept. 20, 1921.

Application filed September 1, 1920. Serial No. 407,371.

To all whom it may concern:

Be it known that we, GEORGE HERBERT BENTLEY and EDMUND GARDNER APPLEBY, both subjects of the King of Great Britain, 5 residing at 12 The Broadway, Westminster, London, England, have invented new and useful Improvements in Apparatus for Agitating the Fuel in Gas-Generators, of which the following is a specification.

10 This invention relates to apparatus for agitating the fuel in gas generators consisting of a poker or pokers which adapt themselves to the height of the fuel.

According to this invention a poker which 15 is balanced by a weight has arms pivoted to it carrying a bar, which arms are connected to the generator by links and slidably mounted upon the poker is a bearing which is supported by a socket on the generator. 20 When the foot of the poker is above the level of the fuel the poker hangs vertically but when the height of the fuel rises and comes in contact with the poker rotary action causes the poker to swing until the 25 poker comes in contact with the bar carried by the arms. The bar prevents any further swinging movement of the poker and causes the poker to rise and slide in the bearing.

The annexed drawings show agitating apparatus made in accordance with this invention.

Figure 1 is a plan, Fig. 2 a section partly in elevation and Fig. 3 shows part of the mechanism when the poker is in its highest 35 position.

The generator α has a top b which is mounted on ball bearings c and rotated by means of a worm d gearing with teeth on the top b . Two pokers e are provided and 40 are similarly mounted. Each poker e is provided with cooling water which enters

through an inlet f and passes away by an outlet g . Each poker has slidably mounted upon it a bearing h resting on a sliding socket j . k are levers each of which is pivoted at l on a bracket p and one end of each lever is pivoted to the poker and the other end secured to a weight m . To the poker are also pivoted arms n carrying a bar o , the arms n being connected to the bracket p on 50 the generator by links q . When the level of the fuel bed is below the foot of the poker, the poker hangs vertically as shown in dotted lines in Fig. 2, the bar o engaging with the top of the bearing h prevents the 55 poker from descending farther than the position shown. When the foot comes in contact with the fuel the poker is swung into the position shown in full lines in Fig. 2 and when the level of the fuel further rises the 60 poker is prevented from swinging by the bar o and is caused to rise into the position shown in Fig. 3.

What we claim is:

1. In a gas generator, a poker, a balance 65 weight connected to the poker, arms pivoted to the poker, a bar carried by the arms, links connecting the arms to the generator and means for rotating the poker.

2. In a gas generator, a poker, a balance 70 weight connected to the poker, a bearing slidably mounted on the poker, a sliding socket on the generator adapted to support the bearing, arms pivoted to the poker, a bar carried by the arms, links connecting 75 the arms to the generator and means for rotating the poker.

In testimony that we claim the foregoing as our invention we have signed our names this 21st day of July, 1920.

GEORGE HERBERT BENTLEY.
EDMUND GARDNER APPLEBY.
